UNITED STATES PATENT OFFICE.

EDWARD A. TUTTLE, OF NEW YORK, N. Y.

EXERCISING-MACHINE.

SPECIFICATION forming part of Letters Patent No. 248,121, dated October 11, 1881.

Application filed March 2, 1881. (No model.)

To all whom it may concern:

Be it known that I, EDWARD A. TUTTLE, of New York, county and State of New York, have invented a new and useful Improvement 5 in Exercising-Machines, of which the following is a specification.

The object of this invention is to contrive a simple arrangement of apparatus whereby a machine with only one pair of handles or levers and a platform arranged for the operator to raise himself by lifting upon said handles or levers may be readily converted into an arrangement for producing the same result by bearing downward on said handles or levers, 10 or one by which the said result may be effected by bearing down on one handle or lever by one hand and lifting on the other handle by the other hand; or both levers may be secured in a fixed position for use as parallel bars.

20 The essential feature of the invention consists of a duplex pivotal connection of the working levers or handles and a detachable brace, together with an adjustable connection of the rods with said levers, which couple them to the platform, whereby the fulcrum is readily shifted from one side to the other of said connection, as it is desired, to raise the platform by lifting or pressing down; and there is a locking device in connection with the platform, 25 connecting-rods, levers, and brace, by which said levers are secured in the position of parallel bars, all as hereinafter more fully described, reference being had to the accompanying drawings, in which—

30 Figure 1 is a side elevation, showing the adjustment for raising the platform by lifting, the parts being in the positions of the beginning. Fig. 2 is a similar view with the parts in the positions which they assume when the platform is raised. Fig. 3 is a side elevation, showing the adjustment for raising the platform by pressing down on the levers, with the positions as at the beginning of the operation. Fig. 4 is a similar view, showing the positions 40 when the platform is raised. Fig. 5 is a side elevation, showing the levers locked in the parallel-bar arrangement. Fig. 6 is a front elevation. Figs. 7 and 8 are details of the detachable brace contrivance, and Fig. 9 is a detail in plan or top view.

A is the frame, to one end of which the platform B is pivoted by the parallel connecting-

bars C, so as to be maintained in horizontal position while suspended by the single pair of connecting-rods D.

E represents the fulcrum-standards, rising up from the same end of the bed-frame to which the platform is pivoted, for supporting the working-levers F; but said levers are pivoted at G to the links H instead of the standards, and the links are pivoted to them at I, and midway between said pivots G and I said links have a brace, J, pivoted to them, and said braces have a series of foot-rests, K, on the standards below pivots I, with which they are 60 detachably connected, both for shifting them up and down to vary the height of the levers and also for dispensing with the braces altogether when the platform is to be raised by lifting, their use being only in the pressing- 65 down and parallel-bar adjustments.

The rods D couple the levers and the platform together. They are pivoted to the latter at M, so as to vibrate or swing thereon from one side to the other of the pivot N, by which brace J and link H are connected, according as the operator is to work by lifting or pressing down, and to vary the leverage for varying the power to be exerted, also to suit the strength of different persons.

80 The connection of the rods with the levers is made adjustable along them by means of the series of stud-pins O, to which said rods, having suitable pin-holes, d, are to be connected detachably; and for regulating the range of the movements of the platform the rods are provided with a range or series of these pin-holes d. Any other form of detachable connection, of course, may be used.

85 The locking device to secure the bars in the position represented in Fig. 5 for parallel-bar exercise consists of the hooks R, attached to the bed-frame in suitable position for engaging the lugs S (see Figs. 5 and 6) when the platform is down and preventing it from rising.

90 It will readily be seen by the foregoing that when the machine is to be used for lifting, as represented in Figs. 1 and 2, the brace J is detached from its foot-rest K, and the levers rest directly on the top of the standards E for their fulcrums, and the rods D are connected to the levers anywhere along the series of holes O, according to the leverage required, the lift being heavier the more the rods are shifted toward

the hands; but when the pressing-down operation is to be executed the braces are adjusted in their foot-rests with said rods D similarly connected to the levers; but the lift is increased 5 by shifting said rods the other way—that is, from the hands and toward the standards E. It will also be seen that with the parts of one side of the platform adjusted for lifting and those of the other side for bearing down- 10 ward the operator may exercise in that manner also, and when he desires the parallel-bar exercise he has only to adjust the braces J in their rests and engage the hooks R with the lugs S.

15 The foot-rests for the braces J consist of metal sockets attached to the side of the standards, into which the lower ends, T, enter to the shoulder W in sufficient length to prevent their disconnection by any shocks or thrusts to 20 which they may be subject in the parallel-bar exercise.

The braces J may be modified according to circumstances. For instance, if the fulcrum standards be extended upward a little above 25 the pivots I, said braces may take the form of suspending hooks or links, and I do not limit myself to the particular arrangement shown.

The levers or handles of this machine are pivoted upon uprights about as high or a little 30 higher above the platform as the hands of a man of average height when standing upright on the platform, so that they range horizontally, or thereabout, when held in the hands by a person at rest, instead of rising up vertically 35 to the hands of the operator as in most other machines. This avoids the necessity of any vertical adjusting devices to the handle for men of different heights, because the handles may be held a little above or below the 40 horizontal position, according as the operator is tall or short; and another advantage is, the leverage may be varied without any change of the apparatus by simply changing the distance of the operator toward or from the fulcrum- 45 standards.

Having thus described my invention, what I claim, and desire to secure by Letters Patent, is—

1. The combination, in an exercising-machine, of a platform, connecting-rods, and working-levers, said working-levers being coupled to the fulcrum-supports by duplex pivotal connections, arranged for readily shifting the fulcrum from one side to the other of said platform, and connecting-rods to enable the operator to raise said platform, either by lifting up or pressing down on said levers, substantially as described. 50

2. The combination, in an exercising-machine, of the platform, working-levers, and connecting-rods, in an arrangement by which the operator may raise the platform by simultaneously lifting on one lever and pressing down on the other, substantially as described. 55

3. The combination, in an exercising-machine, of a platform, connecting-rods, and a pair of levers, and devices for raising the platform by lifting on said levers, and also devices whereby said machine is convertible into an arrangement for raising said platform by 60 lifting on one of said levers and pressing down on the other, substantially as described. 70

4. The combination, with the platform, connecting-rods, working-levers, and fulcrum-standards of an exercising-machine, of the coupling-links H and braces J, said braces having a detachable foot-rest, substantially as described. 75

5. The combination, with platform B, connecting-rods D, working-levers E, connecting-links H, and braces J, of the hooks R, substantially as described. 80

6. The combination, in an exercising-machine, of the platform, lever-standards, connecting-rods, and working-levers, said levers 85 being pivoted on said standards at a point about as high as the hands of the operator when standing at rest on the platform, and ranging horizontally, or thereabout, from said standards to the hands of the operator, substantially as described.

EDWARD A. TUTTLE.

Corrections in Letters Patent No. 248,121.

It is hereby certified that in Letters Patent No. 248,121, issued October 11, 1881, to Edward A. Tuttle for an improvement in "Exercising Machines," on page 2 of the printed specification attached to and forming a part of said Letters Patent, a comma and the word "and" were erroneously inserted in line 55, after the word "platform;" that the proper corrections have been made in the files and records pertaining to the case in the Patent Office, and are hereby made in said Letters Patent.

Signed, countersigned, and sealed this 25th day of October, A. D. 1881.

[SEAL.]

A. BELL,
Acting Secretary of the Interior.
